(57) **CLAIM**

The ornamental design for an cam-locking tamper evidence band closure, as shown and described.

DESCRIPTION

FIG. 1 is an upper perspective view of the cam-locking tamper evident band closure shown in an assembled con-

figuration and shown in use with an environmental exemplary bottle assembly including a cap and neck;

FIG. 2 is a cross-section view of the cam-locking tamper evident band closure taken in a direction of line 2-2 of FIG. 1;

FIG. 3 is a upper perspective view of the cam-locking tamper evident band closure shown in a disassembled configuration, with the exemplary cap and neck in an exploded state;

FIG. 4 is a front view of the cam-locking tamper evident band closure, taken from within portion "4" of FIG. 3;

FIG. 5 is a bottom view of the cam-locking tamper evident band closure, taken from within portion "5" of FIG. 3;

FIG. 6 is a left view of the cam locking tamper evident band closure, taken from within portion "6" of FIG. 3;

FIG. 7 is a right view of the cam locking tamper evident band closure, taken from within portion "7" of FIG. 3;

FIG. 8 is a front view of the cam-locking tamper evident band closure, taken from within portion "8" of FIG. 3;

FIG. 9 is a top view of the cam-locking tamper evident band closure, taken from within portion "9" of FIG. 3;

FIG. 10 is a left view of the cam-locking tamper evident band closure, taken from within portion "10" of FIG. 3;

FIG. 11 is a right view of the cam-locking tamper evident band closure, taken from within portion "11" of FIG. 3;

FIG. 12 is a lower perspective view of the cam-locking tamper evident band closure of FIG. 3 positioned on the exemplary cap of the environmental bottle assembly;

FIG. 13 is a rear view of the cam-locking tamper evident band closure, taken from within portion "13" of FIG. 12; and,

FIG. 14 is a lower perspective view of the cam-locking tamper evident band closure, taken from within portion "14" of FIG. 12.

The dash-dash broken lines represent portions of the cam-locking tamper evident band closure that form no part of the claimed design. Any surfaces inside the bottle form no part of the claimed design. The dash-dot broken lines represent the designation of detail views and form no part of the claimed design.
